United States Patent Office

Des. 222,082
Patented Sept. 28, 1971

222,082

TABLE

Werner L. Kleinert, 37246 Ruth Drive,
Sterling Heights, Mich. 48077

Filed May 15, 1970, Ser. No. 23,011

Term of patent 14 years

Int. Cl. D6—01

U.S. Cl. D33—14

FIG-1

FIG-2

FIG-3

FIG. 1 is a side perspective view of a table showing my new design;

FIG. 2 is a side perspective view similar to FIG. 1 but with the table rotated approximately 90°; and

FIG. 3 is a top elevational view of the table of my new design.

I claim:

The ornamental design for a table, as shown.
